BAG BOTTOMER

Edwin E. Burroughs, Brooklyn, N. Y., assignor to
St. Regis Paper Company, New York, N. Y., a
corporation of New York

Application September 11, 1948, Serial No. 48,820

8 Claims. (Cl. 93—22)

1

This invention relates to bag forming apparatus, and more particularly to apparatus for automatically forming the bottoms of bags such as multi-ply valve bags.

Apparatus of this type which has been proposed in the past for automatically acting upon the end of a bag tube to form a bag bottom, has been subject to certain disadvantages because of the heretofore necessarily slow speed thereof and the consequent low output. One of the reasons for this low output has been the manner in which the bag tubes have been advanced from station to station. This manner as employed in the past has, for example, compromised moving the bag intermittently from one operating station to the next, usually by means of rollers. This method has proven unsatisfactory from many standpoints, particularly from the standpoint of speed above mentioned and the standpoint of lack of positive control over the bag tube as it progresses from one operating unit to the next.

The absence of a master device for controlling the motion of the bag tube as it is progressively operated upon to form a bag bottom therefor, has resulted in a loss of control of the bag in many instances, and has made it impossible synchronously to adjust all of the various units, while running, which form the bottom.

Moreover, it has been impossible in apparatus of this type heretofore proposed to introduce changes in the phase relationships of the various units with reference to a master bag tube conveyor, whereby adjustments can be made in the operation of the individual units while the apparatus is running.

In machines of this type which advance bag tubes intermittently from one station to the next the following disadvantages may appear: misalignment of the tube as it moves through the machine; deformation of bag bottom and valve due to such misalignment; reduction of speed; and the axes of the many rollers which advance the bag tubes must be correctly aligned to an exacting degree, otherwise one roller portion may advance one side of a bag faster than another roller portion.

According to the present invention, a method and apparatus are provided which will eliminate the above noted difficulties or minimize same to such an extent that they are reduced to insignificance.

Various further and more specific objects, features and advantages of the invention will more fully appear from the detailed description when

2

the same is read in connection with the accompanying drawings. It is to be expressly understood, however, that the drawings are for purposes of illustration only and are not intended as a definition of the limits of the invention, reference for this latter purpose being had to the appended claims.

In the drawings,

Fig. 1 is a side elevation of approximately the first half of the machine;

Fig. 2 is a side elevation of the remainder of the machine which is arranged in line with or adjacent to the portion shown in Fig. 1;

Fig. 3 is a top plan view of the portion of the apparatus shown in Fig. 1;

Fig. 4 is a top plan view of that portion of the apparatus shown in Fig. 2;

Figs. 5, 5a, 5b, 5c are enlarged views of consecutively situated portions of the apparatus as shown in Figs. 1 and 2, that is, the lefthand extremity of the apparatus shown in Fig. 5a is in contact with the righthand extremity as shown in Fig. 5, the lines x—x, y—y and z—z upon each of these figures being respectively in contact with one another;

Fig. 6 is a detailed cross-sectional view of the apparatus taken substantially on lines 6—6 of Fig. 2, and showing a sleeve applying apparatus, together with a bottom fold unit and related portions of the device adjacent thereto;

Fig. 7 is a view in front elevation with parts broken away taken on line 7—7 of Fig. 3 showing one of the bottom spreading or opening units;

Fig. 8 is a view partly in section and with parts broken away of the gear trains and control mechanism for the spreader fingers as shown in Fig. 7;

Fig. 9 is a sectional view with parts broken away taken substantially on line 9—9 of Fig. 7;

Fig. 10 is a side view of a power drive shaft assembly for communicating torque to the bottom spreader unit shown in Figs. 7, 8 and 9;

Fig. 11 is a sectional view taken along line 11—11 of Fig. 10;

Fig. 12 is a side elevation partly in section of a sleeve forming and applying apparatus, and a bottom folding unit;

Fig. 12a is a top plan view of a pair of bottom folding shoes or formers which are employed for bending the sides of the bag bottom to close same;

Fig. 13 is an enlarged detailed top view of a portion of the apparatus for forming the sleeves which are applied by the sleeve shown in Fig. 12;

Fig. 14 is a sectional view taken along line

14—14 of Fig. 13 which illustrates a sleeve striker bar adapted for urging sleeves against the cutting edges shown in Fig. 13;

Fig. 15 is a sectional view taken along line 15—15 of Fig. 13 showing in detail a part of the sleeve forming device.

Fig. 16 is a perspective view of a bag tube having one end thereof bent at right angles and being acted upon by a pair of rotating suction arms which pull apart the opposite sides of the tube end in order to permit the insertion of spreader fingers shown here and in Figs. 7, 8 and 9;

Figs. 17a to 17h, inclusive, illustrate steps in the formation of a pasted bag bottom by means of the present invention;

Fig. 18 is a perspective view of a bag tube having the opposite ends thereof bent angularly at approximately ninety degrees to the body of the bag tube, this position being similar to that shown in Fig. 17c; and

Fig. 19 is a detailed perspective view of one corner of a bag bottom formed by the present apparatus, the view being of a corner having a sleeve valve therein, for example, the lower right-hand corner of the bag bottom shown in Fig. 17h.

The form of the invention illustrated in the accompanying drawings, by way of example, comprises apparatus for operating upon the ends of a previously formed bag tube, preferably of the multi-wall variety, whereby automatically a closed and sealed bag bottom is formed on one end and the other end is closed and sealed with the exception of a bag valve. Of course, if desired one or both ends of the bag tube can be formed into a bottom with or without a valve.

Instead of intermittently advancing a bag tube from one operating station to the next, as has been done in the past, the apparatus embodying this invention employs a master bag tube conveying means having a plurality of equally spaced bag tube gripping devices thereon by which bag tubes are successively grasped and continuously advanced to the various operating stations at a uniform but adjustable speed. A common power source is employed for driving not only the bag tube conveyor means but also all of the various units which act upon the bag tube to form the bag bottom. Suitable means are provided, however, for altering the phase adjustments of certain of said units whereby they can be adjusted as desired while the apparatus is in operation.

The novel apparatus comprises, in the form shown, a pair of synchronously driven endless sprocket chains or belts having the above-mentioned plurality of bag tube grippers thereupon which are adapted successively to grasp bag tubes and pull same through the machine in a manner to appear more fully hereinafter. The bag tube grippers act in pairs, one gripper of each pair being mounted on each sprocket chain. Each pair of grippers is automatically closed simultaneously to grip a tube. The tubes are successively and automatically advanced to the grippers by a suitable feeder mechanism (not shown).

After each bag tube has been pulled through the novel apparatus and the bag bottom is formed thereupon, said grippers are automatically opened and the completed bags delivered therefrom seriatim.

Referring now to Figs. 1 to 5, inclusive, the novel bottom forming apparatus is constituted

by a main frame 30 upon which are mounted the various operating units and the bag conveyor means. In the form shown, the latter comprises a pair of endless sprocket chains 31, 32 (Fig. 3) which are respectively stretched between pairs of sprocket wheels 33, 34 and 35, 36 (Figs. 3 and 4).

As shown in Fig. 5, a plurality of bag grippers 37 are mounted upon the endless conveyor chains 31, 32. Each gripper comprises for example a fixed jaw member 37a and a movable jaw member 37b. The latter is pivoted at approximately the center thereof at 37c and urged toward a closed position by a spring 37d which is attached to member 37b and to an arm 37e, the latter, for example, comprising a portion of the link upon which jaw member 37b is pivoted. In order to facilitate the opening of the jaws, a lever is secured to the pivot shaft 37c at 20 and a roller 39 is mounted on the end of such lever and adapted to contact a cam, to appear below, which can force the jaws open against the pressure of spring 37d.

As above mentioned, the grippers act in pairs 25 to grasp the tubes, and suitable means are provided for opening simultaneously the grippers of each pair as the pairs are consecutively moved into a bag gripping position. Such means comprise for example a pair of cams, one 30 for each side of the machine. One of these cams is indicated at 40 (Fig. 5) and is so constructed and arranged that as each roller 39 rides thereupon, the spring 37d is overcome and the jaws of the gripper are temporarily opened. 35 As each roller 39 rolls off of the cam 40, a bag placed between the gripper jaws is immediately clamped and withdrawn from the feeder and advanced into the machine for the formation of the bottom.

40 After the tube ends have been formed into bottoms in a manner to appear more fully hereinafter, the pairs of bag grippers are successively opened by means of cams 41, one of which is shown in Fig. 5c, which releases the bag and permits the removal thereof from the machine.

The main power unit for this apparatus is shown in Figs. 2 and 4 and comprises an electric motor 42 which is in communication with a main drive shaft 43 through the intermediary 50 of suitable pulley and belts 44. In the form shown four V-shaped belts are employed for interconnecting a motor pulley 45 with a power drive pulley 46, the latter being keyed to said shaft 43.

55 Power is communicated to the sprocket wheels which move the sprocket chains 31, 32 by means of a gear train, as shown in Fig. 2, comprising gears 47 and 48, respectively, upon shafts 43 and 49. The latter shaft has attached thereto a helical gear 50 which is in engagement with a second helical gear 51 upon a shaft 52. The sprocket wheels 34, 36 are mounted upon the shaft 52 and thus power is communicated thereto. The sprocket chains 31, 32 along the upper runs thereof rest upon rails 53, 54, as shown in Fig. 6, and the lower runs of these chains rest upon rails 53a, 54a, respectively. The chains are pulled over these rails thereby preventing any sagging which might interfere with the fabrication of the bag bottom. 60 In order to prevent a flapping or occasional arching of the chains 31, 32 upon the upper rails 53, 54, top hold down rails 53b, 54b (Fig. 6) are provided which fit centrally over said chains. Rails 53b, 54b also serve the purpose of holding 65 the chains down when the bag grippers engage 70 the chains.

cams 40, 41. Were it not for such top hold down rails the gripper rollers 39 (and associated lever arm) engaging said cams would urge the chains outwardly without positive gripper operation.

There appears below a discussion of certain of the units for operating upon the tube and tube ends for forming bag bottoms.

Bag tube feeder

A stack of bag tubes is formed adjacent the lefthand extremity of the apparatus, as shown in Figs. 1 and 3, and suitable means are provided for removing them consecutively from this stack and feeding same to the apparatus whereby the bag grippers 37, as above described, successively grasp the bag tubes and pull them at a uniform rate into the machine. Any suitable conventional means may be provided for this purpose.

Slitting unit

Consider, for example, the operation upon a particular bag tube 55 (Figs. 3 and 17) which is grasped by a pair of the gripper devices 37 (Fig. 3) as shown at the left extremity of Figs. 3 and 5. The bag conveyor means thereafter move the bag tube 55 at a uniform rate into a bag slitting unit 56 (Figs. 1, 3 and 5). The function of the slitting unit 56 is to form the slits 55a (Fig. 17) in the bag 55. This is accomplished by means of a pair of rotating knives 56a, one pair for each extremity of the tube end. The rotating knives 56a are secured by means of suitable collars to a rotating shaft 57 (Figs. 1, 3 and 5), the angular relationship between each pair 56 being adjustable in accordance with the width of the particular tube. In the form shown, the knives 56 are angularly separated by approximately 140°.

In order to cut the slits 55a, it is necessary for knives 56a to cooperate with suitable grooved backing members 58 (Fig. 5) which are so constructed and arranged that they rotate in phase relationship with the knives 56a and provide a firm backing therefor to enable each knife to cut into the bag. The grooved backing members 58 rotate upon a suitable shaft 59 (Fig. 5), and the shafts 57, 59 for the knives and backing members, respectively, are geared together by suitable gears 60, 61, respectively (Fig. 1).

As shown in Fig. 1, power is communicated to the slitting unit from the main power shaft 43 by means of the following gear train: gear 62 upon shaft 43, gear 64 upon an intermediate shaft 65 and a helical gear 66 which is in engagement with said helical gear 61 keyed to the shaft 59. Helical gear 66 is mounted upon the intermediate shaft 65. Interposed in said intermediate shaft 65 is a suitable differential 68 which is controlled by a hand wheel 69. The differential 68 is interposed in this gear train for the purpose of making phase adjustments to the knives 56a and their backing members 58 in order to position the slits 55a at desired locations upon the tube ends. Such a phase adjustment of the knives 56a can be accomplished while the apparatus is in motion.

In certain types of bag bottoms the slitting thereof is not desired. Consequently the present invention is not limited to one having such a slitting unit.

Main scoring unit

A main scoring unit next preferably is employed for forming score lines upon the bag tube in order to facilitate the bending of each tube end to a position substantially perpendicular to

the body of the tube, for a purpose to appear hereinafter. Such a unit is indicated as at 70 (Figs. 1, 3 and 5). This unit consists of a pair of scoring rollers 71, one roller for each extremity of the tube, each roller consisting of a thin disc having a periphery which is adapted for forming a suitable fold line as at 72 (Fig. 17b) one fold line in each extremity of the bag tube. Of course, only a single score line can be formed if de-

10 sired.

Cooperating with each scoring roller 71 is a grooved backing roller 73 (Fig. 5), the groove of which is in alignment with the scoring disc.

15 The main score roller 71 is mounted upon a cross shaft 74 (Figs. 1, 3 and 5) which may be geared to rotate with a shaft 75 upon which are mounted the grooved backing rollers 73.

Power is communicated to the scoring unit 70 from the said main drive shaft 43 by means of 20 a gear train comprising a gear 76 upon shaft 43, which meshes with a gear 77 which in turn drives a helical gear 78, the latter engaging a helical gear 79 which drives the above-mentioned shaft 75. In view of the continuous and uniform periphery of 25 the scoring rollers, it is not necessary to adjust their phase relationship to the other units of the machine. However, it is possible to adjust the axial position of at least one of the scoring rollers upon the shaft 74 whereby different sizes of bags 30 can be accommodated. The spaced relationship, for example, of the upper scoring roller 71, as viewed in Fig. 3, can be adjusted by conventional means, for example, by angularly adjusting a threaded shaft 71a having a bracket 71b threaded 35 thereto, the latter communicating an axial thrust to said roller 71 by a yoke at one end thereof.

Tube end opener and spreader

40 Novel means are provided for performing the preliminary opening and spreading operations upon the tube ends to prepare same for (a) the application of adhesive; (b) if desired, the depositing of a valve sleeve; and (c) folding and 45 closing. Said novel means comprise:

(1) A so-called "tube end bender" or "right-angle bender" for the tube ends which moves each tube end about the main score line to a position approximately at right angles to the 50 main body of the tube. It is preferable to employ such a "right angle bender" as at 80 (Figs. 1, 3 and 5) because it positions the tube ends for easy cooperation with the elements for completing the tube end spreading operation. However, 55 the invention is not limited to such a bending device.

(2) A tube end opener as at 81 (Figs. 1, 3, 5) designed to cause a preliminary partial opening of the tube ends to facilitate the action of certain 60 spreader fingers to appear below. The tube end opener opens each tube end as in Fig. 16.

(3) A tube end spreader as at 82 (Figs. 1, 3, 5, 7, 8 and 9).

Each of the above-mentioned units is discussed 65 in detail below.

(1) *Tube end bender.*—In order to prepare each tube end for opening and spreading, it is desirable to bend same, as shown in Fig. 18, about the score lines 72 to a position approximately perpendicular to the main body of the tube. In such a tube end bending device shoe or former 83 engages the outer margin of a tube end and bends same from a position in alignment with the tube body into a position as shown in Fig. 18 substantially at right angles to said tube body. A shoe

or former 84 cooperates with shoe or former 83 for this purpose.

In order to accommodate tubes of differing lengths, the bending shoes 83, 84 can be spread apart or moved closer together by suitable conventional adjusting means.

(2) *Tube end opener.*—After the bag tube has been slit and the end thereof positioned, as shown in Fig. 18, said ends are prepared for opening and spreading. The preliminary step in the opening and spreading operations is shown schematically in Fig. 16 and constitutes a partial opening by means of rotating suction arms having suction cups at the extremities thereof.

The tube end opening unit is indicated generally at 81 (Figs. 1, 3 and 5). One pair of the above-mentioned rotating suction arms is situated on each side of the apparatus for each extremity of the tube. One of these rotating arm suction units will now be described.

As shown in Figs. 3 and 16, a pair of rotating suction arms 85, 86 is shown comprising a pair of conduits having suction cups on the ends thereof, the conduits rotating one in a counter-clockwise direction and the other in a clockwise direction. Conduit 85, in the form shown in Fig. 3, rotates in a clockwise direction and the other conduit in the opposite direction. These conduits rotate synchronously in such a manner that when the suction cups at the extremities thereof are closest one another, that is, when they are in alignment, the tangential components of their motions are in the same direction as the motion of the bag tube. The latter is moving in the direction of arrow 87 (Fig. 16). The two suction cups engage the vertical part of the bag tube end and partially open it at the same time that it is moving forward in the direction of said arrow. When the bag tube end has been so partially opened, a group of fingers moving in synchronism acts thereupon in a spreading operation to be described hereinafter in connection with the above-mentioned spreading unit 82. The suction conduits, in the form shown, move about substantially vertical axes and in arcuate paths in such a manner that by virtue of their angular motion and their engagement of the moving tube ends, partially open same.

The pair of suction arms 85, 86, as shown in Fig. 3 rotate in synchronous relationship because of a geared connection therebetween comprising a bevel gear 89, meshing with a bevel 90 which in turn drives the vertical shaft of the suction conduit 85. A bevel gear 91 is driven by the same shaft as in gear 89 and drives a gear 92 which in turn rotates the suction conduit 86.

Through a similar gear train the rotating suction arms 85a, 86a upon the opposite side of the apparatus are geared for rotation in the same phase relationship as the pair 85, 86. A horizontal shaft 93 (Fig. 3), extending across the machine is adapted for interconnecting the gear trains of the two pairs of rotating conduits.

A suitable device for creating a suction is employed which, in the form shown, comprises a conventional suction pump 94 (Fig. 1) which through suitable conduits is in communication with said suction cups.

As shown in Fig. 16, the suction arms 85a, 86a move toward one another and engage the moving tube end. Continued movement of the bag tube and further angular motion of the suction arms results in said partial opening of the tube ends.

The mechanism for communicating power to the rotating suction arms is shown in Fig. 1 and

is constituted by a shaft 95 which is keyed to the above-mentioned gear 71. The shaft 95, by means of bevel gears 96, communicates torque to said horizontal shaft 93 through the intermediary of another pair of bevel gears 98 (Fig. 3) and a vertical shaft 99 which interconnects said pairs of gears 96 and 98. In order to provide adjustment for the phase relationship of the rotating suction arms relative to the bag conveyor, a differential 100 is interposed in the shaft 95, having suitable manual adjustment means whereby desired corrections can be made in said phase relationship. Such a manual adjustment can be effected through a hand wheel 101 which controls one side of said differential.

The suction arm devices rest mainly upon two parallel stationary support shafts 93a, 93b which extend across the machine. These shafts can act as rails upon which the two pairs of suction arms 20 can be moved relative to one another for adjustments for bags of differing lengths.

(3) *Tube end spreader.*—The main function of this unit is to form the tube ends as shown in Fig. 17d whereby side and corner flaps are spread into position. The "corner flaps" are also sometimes referred to as "end flaps." This spreading unit is also driven by the master power source, there also being a phase adjustment differential interposed in its power drive connection. The tube end spreader is indicated generally at 82 in Figs. 1, 3 and 5, and the details thereof are shown in Figs. 7 to 11, inclusive. Each unit comprises, as above mentioned, a plurality of pairs of fingers which preferably are rotatable upon parallel shafts both driven from the common power source. The above-mentioned rotatable suction arms rotate in a plane which is substantially horizontal. However, the spreader fingers rotate in unison in a plane which is substantially vertical in such a manner that certain of them reach down into the partially opened tube end and further spread the parts thereof, as will appear below. One pair of spreader fingers, designated the "side flap spreader fingers," or "primary spreader fingers" first enters the partly open tube end, the finger striking approximately at the mid point of the inner surface of the tube end. Said fingers are rotating in opposite directions in such a manner that they reach down into and spread out said tube end to form the above-mentioned side flaps by urging the side surfaces of the tube end downwardly and outwardly. Shortly after the commencing of the spreading of the side flaps a second pair of fingers also rotating in opposite directions (and upon the same shafts as said first mentioned pair) is inserted within the opened tube end and strikes same near the inner leading surfaces thereof, forcing same downwardly and outwardly, and forming a leading corner flap, effecting folds along a pair of diagonal fold lines which terminate at the inner extremities of the respective leading slits.

The second pair of fingers is termed the "leading corner flap forming fingers." Means are provided for cyclically varying the speed of rotation of the shaft upon which the spreader fingers are secured, whereby, during each revolution, the speed of rotation thereof is accelerated to a maximum during contact with the tube of said second pair of fingers. This insures insertion within the tube end of said fingers and a proper spreading of the forward corner flap. The speed of advance of the tube end makes it necessary so to speed up the insertion of said second pair of fin-

gers whereby a so-called finger "whipping action" occurs in order that the desired spreading action can take place before the tube end is moved out of range.

The shafts upon which said spreader fingers operate, continue to rotate whereupon, by the time of the completion of preselected angular movement the after corner portion of the tube end is in position for spreading. A third pair of spreader fingers mounted upon respective of said parallel shafts now is effective to engage the after corner portion of the tube end and to spread same, forming a trailing corner flap also having diagonal fold lines.

Referring now to Fig. 7, the operation of this unit in general is as follows: Situated above the bag tube conveyor means, on each side thereof, is a pair of parallel shafts 102, 103 which are parallel to the direction of motion of the bag tubes. Upon these parallel rotating shafts are mounted a left group of fingers and a right group of fingers, as viewed in said Fig. 7. The bag tube 55, also as viewed in Fig. 7, is moving away from us. The shafts 102 and 103 are moving in opposite directions, the former clockwise and the latter counterclockwise, whereby the fingers can reach down into the opened tube end for spreading same.

From the left and right finger groups the following pairs of fingers are constituted:

(1) *Side flap spreader fingers 104, 105.*—The fingers of this pair, rotating in opposite directions, are adapted for reaching down into the partially opened tube end for providing the initial spreading action. These fingers initially strike the tube end preferably at or near points 106, 107, respectively, as shown in Fig. 17d. The action of these fingers upon the tube end is to spread outwardly the side flaps and thereby to provide an inward pulling action upon the corner flaps, in particular the leading one. Such side flaps are indicated in Fig. 17d at 108 and 109, and the corner flaps are indicated at 110 and 111, the former being the leading corner flap.

(2) *Leading corner flap forming fingers 112, 113.*—The angular position of the leading corner flap fingers 112, 113 is preferably somewhat behind that of the pair 104, 105, that is, there is a slight angular displacement between these pairs whereby the second pair will enter the open tube end after the first pair, and will strike inside the leading corner flap preferably at or near points 114, 115, respectively (Fig. 17d), which in the form shown are about five-eighths of one inch from their respective leading diagonal fold lines.

The angular velocity of fingers 102, 103 varies cyclically, as above mentioned, and reaches a maximum during the period that said fingers are in contact with said tube end, preferably at or shortly after the point of first contact. Fingers 102, 103 draw down thereover a portion of the leading corner flap during a so-called "finger whipping action" which positively forms said leading corner flap and its diagonal fold lines as at 110a, 110b (Fig. 17d) before the tube end, by virtue of its forward motion, can move out of range.

Before fingers 112, 113 become disengaged from within the tube end, the tube preferably enters between a pair of pinch rollers 116a, 117a (Figs. 5, 9) which assists in folding the now spread tube ends.

(3) *The trailing corner flap spreading fingers 116, 117.*—This pair of fingers is so situated an-

gularly relative to the other two pairs that it will be in position to spread the trailing corner flap 111 (Fig. 17d) substantially immediately after the spreading of the leading corner flap 110.

The cyclical variation in angular velocity of the spreader fingers is accomplished, for example, by a pair of meshing eccentric gears as shown at 118, 119 of Fig. 10. These gears are so arranged in the power drive gear train of the spreader fingers that the angular speed of the leading corner flap fingers 112, 113 is at its greatest when said fingers are acting upon the tube end. In other words, there is a rapid insertion and wiping action of these fingers as caused by the above-mentioned eccentric gears and thereafter a relatively slow angular motion and a subsequently quick or very rapid repetition of said wiping action. After the completion of the action of said pairs of fingers 104, 105, and 112, 113 the third pair of fingers thereafter strikes the trailing corner flap 111 preferably at or near the points 120, 121, respectively (Fig. 17d) and spreads same.

(4) The spreader fingers are mounted upon their respective shafts, as shown for example in Fig. 9 with respect to fingers 105, 113 and 117, by means of suitable adjustable mounting blocks 105a, 113a and 117b, respectively. The angular ad-

justment of each of these mounting blocks, of course, can be varied in order to provide the proper angular relationship therebetween to accomplish the spreading of said side and corner flaps. Said fingers 105, 113 and 111 preferably are threaded at the extremities thereof nearest the shaft 103 in order to permit insertion into suitable bores in said mounting blocks whereby a precise and fine control of their position relative to the bag tube can be obtained. Suitable means, such as bolts, can be employed for securing the fingers in the blocks firmly in their final adjusted positions.

Regarding the shapes of the fingers, reference is made to Figs. 7 and 9, with special reference to fingers 105, 113 and 117 which are illustrative. As viewed in Fig. 7, finger 105 is in the form of an L with the base thereof slightly curved. When finger 105 is in position mounted within its block 105a, it is seen that the threaded portion thereof is removed from the axis of its shaft 103 in such a manner that the rotatable portions, including both finger 105 and block 105a, becomes in effect U-shaped. The fingers 104, 105, of course, are so constructed and arranged that when they are rotating, respectively, in clockwise and counterclockwise direction they are pointed downwardly into the open tube end at approximately the time of their first insertion into the tube end and thereafter will be inserted deeper, and will partake of a spreading and wiping action.

Regarding finger 113 (and its mate 112) as viewed in Fig. 7, this finger also is substantially L-shaped. However, as viewed in Fig. 9, it will be seen that the extremity of this finger is provided with a protuberance or arm 113b which extends in the direction of motion of the bag 55. The function of this protuberance or extension is to permit or facilitate the spreading out of the leading corner flap whereby the flap will be drawn down over said protuberance. Thus the diagonal fold lines 110a and 110b will be more positively formed and will be prepared for insertion into the pressing or pinching rollers 116a and 117a (Fig. 9).

With reference to finger 117, one projection

thereof as viewed in Fig. 7 is L-shaped as are those of the first two discussed fingers. In order to assist this finger in moving across the trailing corner flap 111, an angularly disposed elbow portion is provided as at 117c to which is attached an arm or extension 117d. The latter enables the finger to sweep over a wider area than ordinarily possible. If the angularly disposed elbow portion 117c were not provided, it is possible for the trailing corner flap 111 to become bent backwardly in the wrong direction when it comes into engagement with the rotating finger 117. The direction in which the protuberance 117d extends is in the direction of motion of the bag 55, as shown in Fig. 9.

As shown in Figs. 3 and 9, the spreader units 82 are mounted upon a pair of parallel support shafts 122 and 123 which extend across the path of the bag tubes and are mounted in suitable supports attached to the main frame 30 (Fig. 1).

A description of the means for mounting the righthand unit 82 will be given, it being understood that the lefthand mounting is analogous but adapted for the lefthand side of the machine.

Mounted upon said shafts 122, 123 is a housing 124 (Figs. 7, 8 and 9) within which is located the gear train for transmitting power from the main power drive to the shafts 102, 103.

The distance between both left and right spreader units 82 can be adjusted by suitable conventional means in order to accommodate bag tubes of varying lengths.

Supported between said shafts 122, 123 in suitable journals is a power shaft 126 which constitutes a part of the power transmitting mechanism from the main power source (motor 42) in a manner to appear more fully hereinafter. Shaft 126 also extends across the apparatus and is parallel to the shafts 122, 123.

Shaft 126, as shown in Fig. 8, communicates torque to the shafts 102, 103 and hence to the spreader fingers, through the intermediary of a gear train which has interposed therein a resilient member which gives to the spreader fingers a "resilient touch" upon the bag tube end whereby a yielding engagement thereof is attained. This is necessary in order to avoid a tearing of the tube ends.

Referring to Fig. 8, torque is transmitted to said shafts 102, 103 by means of the following members: (1) a sleeve member 127, which preferably is keyed to the shaft 126. A key 127a is shown in Fig. 9 for this purpose. (2) Adjustably secured to sleeve 127 is an angularly adjustable collar member 128 (Figs. 8 and 9) having a bore therethrough adapted for fitting over one extremity of said sleeve 127, one extremity of collar 128 being clamped upon said sleeve 127 by means of a threaded bolt 129 (Fig. 9). At the opposite extremity of said member 128 is a protruding arm 128a (Figs. 8, 9) which is operatively connected to the remainder of the gear train through the intermediary of a resilient member such as a coiled spring shown in section at 130 (Fig. 8). (3) Said resilient member 130 is in engagement with a gear 131 by means of a stud member 132 which is secured thereto by means of a suitable nut and bolt 133. The stud 132 extends through an arcuate slot which is formed within a flange 127b of the sleeve 127. The function of the slot is to provide a bearing surface for the stud 132 to accommodate its angular motion which is caused by the flexing of spring 130. The spring 130 is compressed as a result of the fingers 112, 113 meeting with resistance when they draw down

over themselves the corner fold 118. (4) The above-mentioned gear 131 is, in the form shown, of the helical variety which is adapted for transmitting torque to another helical gear as at 132a. (5) The final gear of this gear train is a helical gear 133a which is in engagement with said gear 132a, and to which is attached the shaft 103.

Torque is communicated to the shaft 102 by means of suitable helical gears 134 and 135, as shown in Fig. 8.

A suitable double bearing 136 is provided for the shaft 102, as shown in Fig. 9, and a similar one is employed for the shaft 103.

It is necessary to provide means for spreading apart or bringing together the shafts 102, 103 to any desired position of adjustment in order to accommodate bags of varying sizes and tube ends of varying lengths having side and corner flaps of differing sizes.

Such means are shown in Figs. 7, 8 and 9, with particular reference to Fig. 7, and comprise a pair of angularly shiftable brackets 137, 138 upon which the shafts 102, 103 are mounted. Brackets 137, 138 are respectively mounted for angular movement about the center shafts 139, 140 of the helical gears 132a, 134.

The angular position of the brackets 137, 138 are controlled synchronously by a pair of worms and worm wheel segments, 141, 142, respectively (Fig. 7). Worms 141, 142 are mounted upon a common adjustment shaft 143 which is controllable by a hand wheel 144. The worms 141, 142, of course, are in opposite directions in order that the brackets 137, 138 may be spread apart or moved closer together simultaneously.

In order to accommodate this angular movement of the brackets 137, 138, suitable arcuate slots 124a, 124b (Fig. 7) are cut in the housing 124.

When an adjustment is made by means of handwheel 144 friction normally may hold said brackets in adjusted position. However, vibration of the apparatus may upset this adjustment which makes it desirable to provide an additional locking mechanism for holding the brackets in a fixed position once an adjustment has been made. Such a locking mechanism for bracket 137 is shown as at 145 in Fig. 7. This mechanism communicates a clamping action to the bracket 137 in a conventional manner and clamps in position an arcuate slotted arm 146 (Fig. 7) rigidly secured to bracket 137.

A locking mechanism 147 is provided for bracket 138 which is adapted for cooperating with an arcuate slotted arm 148 in a manner analogous to mechanism 145.

Torque is communicated from the main drive shaft 43 to the shaft 126 (Fig. 9) as shown in Figs. 1 and 10 as follows: An intermediate shaft 149 is operatively connected to the main power shaft 43 by means of suitable gears 150, 151. Secured near one extremity of shaft 149 is a suitable helical gear 152 which is in mesh with a gear 153. The latter drives the lower press roller 117a (Figs. 5 and 9). The upper of these rollers 116a is positively driven by means of a gear 154 which also is in mesh with the gear 153.

The shaft of roller 117a is indicated as at 156 (Figs. 5 and 10) and communicates torque to the above-mentioned shaft 126 through the intermediary of the gear train illustrated in Fig. 10. In Fig. 10 a pair of bevel gears 157 communicates torque from the shaft 156 to a vertical shaft 158 to which the above-mentioned eccentric gear 118 is secured. A parallel shaft 159 has secured there-

13

to the other of the two eccentric gears 118 and the torque is thence passed to the spreader finger drive shaft 126 by means of a pair of bevel gears 160 (Fig. 10).

The action of the eccentric gears 118, 119, as explained above, is adapted to give the highest angular speed to the rotating spreader fingers 112, 113 when they are actually in engagement with the tube ends. The angular speed of these fingers (112, 113) is lowest when they are near the high points of their angular paths. Their angular velocity uniformly increases to a maximum during the down stroke and then uniformly decreases to a minimum. The point of maximum speed can be governed by adjusting the positions of the gears 118, 119.

In addition to the above-described adjustments to the angular positions of the spreader fingers by means of the handwheel 144, a differential 149a (Figs. 1 and 3) is interposed in the intermediate shaft 149 for the purpose of permitting adjustment to the phase relationship of said rotating fingers with the movement of the bag conveyor. A suitable handwheel 149b is provided for introducing such adjustment.

Pressing unit

After the bag tube 55 has been acted upon by the spreading fingers above described and drawn through the pressing rollers 116a, 117a, a subsequent pressing action is imposed upon the now partially formed bag bottom by means of a pressing unit 161 (Figs. 1, 3 and 5). This unit is constituted by a pair of cooperating rollers 162, 163 which further exert an ironing or pressing action upon the spread corner and side flaps. Rollers 162, 163 are driven by shaft 149 (Fig. 1) by means of gears 162a, 163a, the latter meshing with a gear 163b on said shaft 149.

Bottom fold line scoring unit

Thereafter the spread tube end is subject to a fold line scoring unit which forms therein the bottom fold lines 164, as shown in Fig. 17e. This unit is a double scoring unit and determines the width of the bag bottom because upon the lines 164 the side flaps and portions of the corner flaps are folded over to form the bag bottom.

This unit is indicated in Fig. 1 at 165 and is constituted by two pairs of rollers roughly similar to the above-described main scoring roller 71 (Fig. 3), there being one pair of the double scoring rollers for each end of the tube. As shown in Fig. 3, each pair comprises scoring rollers 166, 167 which are held in spaced relationship upon a rotating shaft 168. The latter extends across the machine and is rotated by means of a suitable gear train from the main power shaft 43 in a manner to appear below. The scoring rollers 166, 167 are adjustably mounted upon said shaft 168 and can be positioned in any desired spaced relationship by means of conventional collar locking devices. The distance between the scoring rollers 166, 167 determines the width of the final bag bottom because, as above mentioned, the folding thereof is effected along said bottom fold lines.

In view of the continuous and circular confirmation of the scoring rollers 166, 167, it is not necessary to introduce any correction to their phase relationship and consequently a non-adjustable gear train communicates power to these rollers. This gear train is illustrated in Fig. 1 and is constituted by gears 169 and 170

14

which communicate torque to a shaft 171 to which is secured a helical gear 172. The latter is in mesh with another helical gear 173 which drives a shaft 174. Upon the latter shaft are mounted pairs of grooved rollers for cooperating with the main scoring rollers 166, 167. Furthermore, the gear 173 communicates torque to the shaft 168 by means of still another helical gear 175 which is keyed to said shaft 168.

Adhesive or paste applicator

An adhesive or paste applicator is indicated generally in Fig. 1 at 176. This applicator is constituted by a pair of rollers 177, one pair to each side of the apparatus. As shown in Fig. 5a, the two cooperating rollers 177 rotate together by virtue of a gear interconnection which is formed by suitable gears 178, 179. Furthermore, the upper rollers 177 are provided with a so-called "high segment" for the purpose of communicating adhesive or paste to preselected edge areas of the corner and side flaps of the spread bag bottom. The shape of the paste applying "high segment" is identical with the shape of the area to which paste is applied, for example, as shown in Fig. 17f. The "high segment" of the top roller 177 is adapted for applying the paste or adhesive in a conventional manner. In contact with the top paste applying roller is an intermediate roll 180 which also is in engagement with a paste roll 181, the latter being partially immersed in a bath of adhesive or paste. In order to spread a coat of adhesive smoothly upon the roll 181, a suitable subsidiary or coat flattening roll 182 is provided (Fig. 5a). The paste roll 182 is intermittently shifted angularly by means of a suitable pawl and ratchet device 183 (Fig. 1), the pawl being driven by an eccentric 184 upon the shaft of the top roll 177.

Sleeve forming and applying mechanism

Mechanism is next provided for forming a sleeve 186 (Figs. 17g and 19) and depositing same upon the spread tube end preferably adjacent the leading corner thereof, and thereafter folding the spread tube end along the above-mentioned bottom fold lines 164, to form a finished bag bottom as illustrated in Fig. 17h.

Such a unit is illustrated generally at 187 (Fig. 2) and is illustrated in more detail in Figs. 4, 5b, 6, 12, 13, 14 and 15.

A reel of paper is indicated at 188 (Fig. 2) from which the sleeves are formed in a conventional sleeve forming device. Sleeves are cut from the strip comprising said roll, formed, and grasped by a rotating drum 189, by means of suitable grippers, and deposited upon the pasted tube end in the position shown in Fig. 17g above mentioned.

A web 188a of the paper 188, as shown in Fig. 2, is fed over suitable rollers 190, 191 and 192 (Fig. 2) to a mandrel or former 193. This mandrel is also shown in Figs. 12 and 13. The web 188a is folded over said mandrel under the action of a pair of rollers 194 and 195 which are preferably of a resilient material such as rubber and mounted upon pivoted arms 196 and 197, respectively.

An adhesive or paste is applied to one of the edges of the web 188a by means of a sleeve seam paste applicator 198 (Fig. 2) whereby one of the edges of the web, as at 188b (Fig. 13), is provided with a thin strip of adhesive.

The web 188a, after having been folded and

15

pasted, as shown in Fig. 13, is pulled through the sleeve forming apparatus by means of a pair of rollers 199 (Figs. 12 and 15), to which a torque is transmitted in a manner to appear more fully hereinafter.

After the folded sleeve has been drawn through the rollers 199, it is thrust into the "cut-off" area 200 (Fig. 15) where a pair of cutting edges 201, 202 are effective in combination with a striker arm 203 (Figs. 14 and 15) to sever the sleeve from the web, whereupon it is further pressed and grasped by the above-mentioned sleeve applying drum 189 (Fig. 2).

In order to form a sleeve 186, as shown in Fig. 19, having an overlapping leading edge 186a which hangs over the lower lip 186b thereof, the cutting tool 201 is of arcuate shape and is situated below the straight serrated cutting tool 202.

The striker arm 203 is rotated in timed relationship with the sleeve forming apparatus whereby it strikes the sleeve immediately beneath and slightly forward of the cutting edge 201 whereby the above-described overhanging arcuate leading edge 186a (Fig. 19) is formed. Thereafter the straight portion of the sleeve is formed by thrusting same against the cutting edge 202.

As shown in Fig. 12, a pair of sleeve gripping devices 205 are mounted diametrically opposite one another and adjacent the periphery of the sleeve applying drum 189. Grippers 205 are controlled, for example, by suitable cam devices which cause same to close and grasp a completed sleeve and pull it away from the sleeve forming apparatus, whereupon it is carried in the direction of the arrow and deposited upon the oncoming bag tube. Each gripper 205 is mounted upon a suitable shaft 206 having a gear 207 secured thereto which is in engagement with a toothed segmental member 208 which is pivoted at 209. The segmental member 208 is urged in a counterclockwise direction by means of a spring 210 which thus urges the gripper 205 toward a closed position.

The gripper opening and closing control means is constituted by a cam 211 which is fixedly mounted and which is adapted for angularly shifting said segmental members 208 by means of an arm 212 having a roller secured to the extremity thereof. Said arms 212 are either secured to said segmental member 208 or rigidly attached to the pivotal mounting 209 therefor.

Only two sleeve gripping devices 205 are shown, one of these being adapted for gripping a sleeve which has been severed just prior to the time when a diametrically opposed sleeve is being deposited upon the bag bottom.

The sleeve applying drum 189 has two areas, 189a, 189b, upon the periphery thereof which are higher than the remainder of the periphery. The high portions serve the purpose of pressing downwardly the glued sleeve to the pasted spread tube end. That is, the high portions 189a, 189b, are adapted for firmly affixing the sleeve to the glued portions of the tube end, as shown in Fig. 17g.

The sleeve gripping devices 205, as shown in Fig. 12, are diametrically opposed upon the drum 189. The sleeve gripper in the uppermost position (Fig. 12) has just closed upon a sleeve in order to withdraw same from the sleeve forming device. The closing of the gripper occurs by virtue of disengagement of the arm and roller 212 with the stationary cam 211.

The sleeve gripper 205 in the lowermost position in this figure is held closed under the influence of spring 210 and will so remain until its

16

opening arm and roller 212 engages the lowermost portion of the cam 211, whereupon the sleeve will be released in the desired location (Fig. 17g).

The above-described rollers 199 (Figs. 13 and 15) preferably are constituted by one superposed pair on the left side of the sleeve and another pair on the right side. These pairs of rollers are in spaced relationship upon shafts 199a and 199b. Each pair of superposed rollers 199 (Fig. 15) are adapted for gripping the sleeve and pressing same directly therebetween without the interposition of any part of the mandrel 193. The latter, as shown in Figs. 12, 13 and 15, is provided with a portion 193a which is substantially horizontal, and another upwardly slanted portion 193b which is in alignment with the oncoming paper web. The left-hand extremity of the horizontal portion 193a (Fig. 15) has formed thereon the above-described serrated cutting edge 201 for the formation of the arcuate overhanging portion 186a of the sleeve 186. Suitable indentations as at 193c are provided on either side of the mandrel in order to permit the rollers 199 directly to press between them the folded sleeve.

Rollers 213, 214, which are moved in timed relationship with the rotating drum 189 and the remainder of the sleeve forming apparatus, act as retarders to produce an arc in the paper web to avoid improper cutting against the cutters 201, 202.

Torque is communicated to the sleeve forming apparatus by means of the following transmitting mechanism: A gear 215 upon main power shaft 43 drives a shaft 216 by means of a gear 217 meshing therewith. Shaft 216 drives a transverse shaft 217a by means of engaging helical gears 218 and 219, respectively. Upon the latter is mounted a roller 220 (Fig. 12) which cooperates with drum 189, whereby the sleeves are pressed upon the bag bottom. A similar roller 221 (Figs. 4 and 6) is mounted upon the shaft 217a on the opposite side of the machine to provide a backing for the pressing of a sleeve upon the opposite bag bottom if so desired.

Central grooves 220a and 221a are formed in the rollers 220, 221, respectively (Fig. 6), in order to accommodate the fingers of sleeve grippers 205.

As indicated in Figs. 6 and 12, the rotatable drum 189 is mounted for rotation upon a shaft 222, and said drum can be shifted from one side of the machine to another and clamped in a desired position. Suitable keying means are provided to facilitate such axial movement of drum 189. Torque is communicated to the shaft 222 from the shaft 217a (Fig. 6) by means of shaft 223 and suitable bevel gears 224 and 225.

Torque is transmitted to the rotating striker arm 203 and to the rollers 199, 213, 214, as shown in Figs. 4, 6, 12 and 13, by means of a helical gear 226 which engages another such gear 227 which rotates upon a shaft 228 perpendicular to that of gear 226. Shaft 228 rotates within suitable journals as at 229, 230 (Figs. 4, 13). Shaft 228 is in operative engagement with the roller 213 by means of bevel gears 231. Moreover, said shaft 228 has secured thereto a flange 232 to which is attached said striker bar 203. Fine adjustments to the position of striker bar 203 can be made by virtue of its mounting upon the flange 232 (Fig. 14). An arcuate member 233 is provided at the base of the striker bar for attachment to the flange 232, and arcuate slot 233a is formed in said member through which a suitable securing means, such as a bolt 234, 75 can be inserted for adjustably positioning the

striker bar, within the limits of said slot, about a pivot 235.

The rollers 199 are operatively associated with the roller 213 by means of a gear train made up of gears 236, 237, 238 and 239 (Figs. 12 and 13).

Thus all of the rotating elements of the sleeve forming unit operate in timed relationship to one another and to the master bag tube conveyor.

Adjustment of the phase relationship of said bag tube conveyor and the sleeve forming unit can be made manually while the apparatus is in operation by means of a differential 216a (Fig. 2) which is interposed in said shaft 216 and which is provided with an adjustment handwheel 216b. An angular adjustment made to the handwheel 216b, of course, will not destroy a predetermined adjustment of the various rotating elements of the sleeve forming unit relative to one another but it will advance or retard the depositing of a sleeve upon the bag bottom.

Bottom fold unit

After the sleeve 186 has been deposited upon the spread tube end, as shown in Fig. 17g and therein pressed in place, the side flaps 108, 109 and portions of the corner flaps 110, 111 are folded along the side fold lines 164 to the position shown in Fig. 17h, whereupon the tube end is finally formed into a completed pasted bag bottom and may then be ironed or pressed.

The bottom folding mechanism is shown in Figs. 4, 6, 12 and 12a, there being one pair of bottom folding shoes or formers on each side of the apparatus, one for each extremity of the bag tube.

Referring particularly to Fig. 12a, one of the bottom folding units is indicated at 240 comprising an inner flap folding shoe 241 and an outer flap folding shoe 242. These shoes are mounted parallel, the areas first encountered by the bag bottoms as at 241a and 242a being substantially horizontal. The inner margins or edge areas of the shoes 241, 242 remain horizontal and coplanar with the above-mentioned areas 241a, 242a. However, the outer margins of each shoe is formed so that it progressively folds over said horizontal inner edge, the folding over of shoe 241 occurring at 241b and of shoe 242 at 242b. The point of complete folding of shoe 241 is in advance of that of shoe 242 in order to insure that the inner side flap 108 is folded over first whereupon the outer side flap is superimposed thereupon and prepared for final pressing.

Final bag bottom pressing unit

The bag tubes having their bottoms folded, as in Fig. 17h, next preferably are delivered to a bottom pressing unit indicated at 243 (Figs. 2 and 4). This unit is constituted by two pairs of rollers 244, 245 (upper and lower, respectively), one pair for each extremity of the bag. These rollers lightly press together the folded bag bottoms to insure a positive adhesion between the adhesive bearing portions of the bag bottom. The pressure is light to avoid expelling the paste.

Bag delivery unit

As indicated generally at 246 (Figs. 2, 4 and 5c), a bag delivery unit is provided comprising elastic belt 247 which passes over an upper final delivery roller 248 (Fig. 2), and which also passes over the upper rollers 244. The lower run of belt 247 cooperates with a flat, horizontal surface 249 over which it passes with completed bags interposed therebetween. The direction of motion of the lower run of the belt is, of course,

from left to right, as viewed in Fig. 5c, whereby the completed bag is delivered from the machine.

Torque is communicated to the pressing rollers 244, 245 from the above-mentioned shaft 49 by means of a pair of helical gears 250, 251 (Fig. 2), the latter being in engagement with a suitable helical gear 252 for rotating the upper of the two pressing rollers 244.

The belt 247, being in engagement with the upper of the rollers 244, thus is put in motion to deliver the bags.

The operation of this apparatus has been described in connection with the individual elements above set forth.

There is thus provided novel means for forming the bottom of a bag from the bag tube. Bag tubes of the multi-layer variety can be successively operated upon by this apparatus, particular reference being had to bag tubes having so-called stepped ends, for example, as shown in the Patent 2,055,030, granted September 22, 1936. However, it is possible to form bag bottoms upon bag tubes having ends which are not similarly stepped and which have greater or less number of plies. The novel bag bottom forming apparatus is capable of a heretofore unattained output of about one hundred fifty bags per minute.

Although only one embodiment of the present invention has been illustrated and described in detail, it is to be expressly understood that the invention is not limited thereto. Various changes may be made in the design and arrangement of the parts without departing from the spirit and scope of the invention as the same will now be understood by those skilled in the art. For a definition of the limits of the invention, reference will be had to the appended claims.

What is claimed is:

1. In an automatic bag bottom forming apparatus, a bag tube conveyor, including spaced gripping means for consecutively gripping a plurality of bag tubes near opposite extremities along the leading edges thereof; and moving same in succession relative to said apparatus in preselected spaced relationship; mechanism for consecutively spreading a tube end of each of the tubes moved by said conveyor and forming thereupon side and end flaps, said spreading mechanism including a supporting member mounted for rotation about an axis substantially parallel to the path of bag tube movement, such spreading mechanism thus being angularly shiftable upon such supporting member about such axis, means for mounting said spreading mechanism against movement in the direction of such path of bag tube movement; mechanism for applying adhesive consecutively to the spread tube ends upon a preselected area thereof; folding mechanism for acting consecutively upon the tubes for folding at least one side flap of each tube over another side flap thereof; and mechanism for operatively connecting said conveyor with said spreader and adhesive applying mechanisms for maintaining a preselected phase relationship therebetween, said conveyor moving continuously the bag tubes in succession relative to said mechanisms.
2. In an automatic bag bottom forming apparatus, the combination comprising, a bag tube conveyor; mechanism for moving said conveyor at a predetermined speed; mechanism for preliminarily opening the end of a bag tube which is conveyed by said conveyor to facilitate the spreading of the tube end; a pair of angularly shiftable side flap spreader fingers for reaching into the preliminarily opened tube end and

spreading same to form side flaps thereupon; a pair of angularly shiftable leading corner flap forming fingers for reaching into the tube end near a leading edge thereof and drawing a portion of the tube end thereover forming a leading corner flap; a pair of angularly shiftable trailing corner flap forming fingers for engaging the tube end near the after portion thereof and forming a trailing corner flap; means for mounting said fingers including a supporting member mounted for rotation about an axis extending substantially parallel to the direction of bag tube movement, such spreader fingers thus being angularly shiftable about such axis, means for mounting said supporting member against movement in the direction of such path; mechanism for operatively interconnecting said bag tube conveyor and fingers for motion in a predetermined timed relationship; mechanism for applying adhesive to a predetermined area of the spread tube end; and mechanism for folding one side flap over the other side flap for forming a bag bottom.

3. A bag bottom opening and spreading device comprising in combination: a conveyor for advancing a bag tube along a predetermined path including grippers for grasping the leading edge of such tube near the opposite extremities thereof; mechanism for bending an end of said tube to a position approximately at right angles to the body of the tube; mechanism for thereafter partially opening the tube end; and a tube end spreading unit comprising a plurality of pairs of fingers which move angularly in synchronous relationship to one another and to said conveyor, one of said pairs being adapted for entering the partially open tube end and spreading same to form side flaps for a bag bottom, a second pair of fingers adapted for entering said open tube end near the leading edge thereof for folding same thereover along diagonal fold lines to form a corner fold flap, and a third pair adapted to engage the tube end near the trailing edge thereof and folding same along diagonal fold lines to form a second corner fold flap.

4. In apparatus of the class described, the combination comprising: a bag tube conveyor including, mechanism for positively gripping a bag tube; power mechanism for moving said bag conveyor means; a main fold line scoring unit for forming a main fold line near one extremity of a bag tube and substantially parallel thereto; mechanism for bending said bag tube along said main fold line to a position substantially perpendicular to the main body of the tube; mechanism for partially opening a bag tube end; a pair of side flap spreader fingers rotatable in opposite directions and so constructed and arranged that said fingers reach down into and spread apart the partially opened tube end; a second pair of spreader fingers rotatable upon an axis which is fixed relative to said gripping mechanism and adapted for reaching into and further spreading the partially spread tube end in the region of the leading edge thereof while the latter is moving away therefrom thereby pulling over such fingers a portion of the leading edge region and forming a leading corner flap having diagonal fold lines; a third pair of spreader fingers adapted for engaging the trailing corner flap of said tube end and spreading same; mechanism for moving said spreader fingers in timed relationship with said bag conveyor means; mechanism for applying adhesive to preselected areas of the side and corner flaps of said tube end; and a tube end folding unit in the path of the advancing tube

end for folding the side flaps of the spread tube end to form a bag bottom.

5. A bag bottom forming mechanism comprising in combination: bag tube conveyor; mechanism for moving said conveyor at a uniform speed; a plurality of means for securing bag tubes to said conveyor means each along a leading side edge thereof whereby the tubes are pulled sideways transversely to the longitudinal axis thereof; means for actuating consecutively said bag securing means whereby bag tubes are gripped and pulled consecutively thereby; a main bag bottom scoring unit situated in the path of bags moved upon said conveyor for forming a main bend line near the extremity of said bag tube about which the tube end can be bent; a tube end bending unit for angularly shifting said tube end to a point substantially perpendicular to said tube; a pair of angularly shiftable suction devices operating in timed relationship to said bag conveyor means for applying suction to opposite sides of said bent tube end for opening same; a tube end spreading unit comprising a pair of side flap spreading fingers which shift angularly in synchronism and in timed relation with said bag conveyor means, said fingers being adapted to enter the tube end and to spread same forming bag bottom side flaps, a pair of corner flap forming fingers also rotatable in synchronism and in timed relation to said bag conveyor means for entering said open tube end in the region of the leading corner thereof while the latter is moving away therefrom thereby pulling over such fingers a portion of such leading corner region and forming a leading corner flap having diagonal corner fold lines, a second pair of corner flap forming fingers also shifting angularly in synchronous relationship to one another and to said bag conveyor means for forming a trailing corner flap; mechanism for forming side fold lines upon said spread tube end; mechanism for applying adhesive to preselected areas of said spread tube end; and mechanism for folding said side flaps along said side fold lines whereby the bottom of the bag is closed and sealed.

6. In a bag bottom forming apparatus, the combination comprising: endless belt mechanism; mechanism for moving said endless belt at a preselected uniform speed; a plurality of spaced bag grippers mounted upon said endless belt; mechanism for actuating said bag grippers consecutively as each gripper passes a preselected point in the path thereof whereby a bag tube is grasped and moved therewith; a bag tube slitter unit operating in synchronism with said endless belt means for forming a plurality of slits in the end of tubes which pass thereby; a main scoring unit for forming a main score line upon each tube end about which the tube end can be bent; a bender unit for bending said tube end along said main score line to a position substantially perpendicular to the bag tube; suction means for opening said tube end, said suction means comprising a pair of synchronously moving conduits each being in communication with suction means, said suction conduits moving in timed relationship with the movement of said endless belt means; a tube end spreader unit comprising a pair of synchronously moving primary fingers which are adapted for entering the tube end opened by said suction cups and spreading same apart to form side flaps of a bag bottom, a pair of synchronously moving secondary fingers which are adapted for entering said open tube

end near the leading edge thereof and spreading same to form a leading corner flap folded along diagonal fold lines, and a third pair of fingers which move in synchronous relation for forming a trailing corner flap folded along diagonal fold lines; mechanism for applying adhesive along preselected areas of said side and corner flaps; side fold line scoring mechanism for forming a pair of parallel side fold lines upon said spread tube end; and mechanism for folding the spread tube end along said side fold lines to close same and form a pasted bag bottom.

7. In an automatic bag bottom forming apparatus, the combination comprising, a bag tube conveyor; mechanism for advancing said conveyor at a preselected speed; a tube end spreader mechanism for spreading the end of a bag tube conveyed by said conveyor, including a pair of angularly shiftable side flap spreader fingers adapted for reaching into the tube end and spreading same to form side flaps thereupon, a pair of angularly shiftable leading corner flap forming fingers operatively associated with said side flap spreader fingers and also adapted to reach into the tube end near the leading edge thereof and to pull thereover a portion of the tube end thereby forming a leading corner flap having diagonal fold lines, and a pair of angularly shiftable trailing corner flap spreading fingers operatively connected to said other pairs of fingers and adapted for engaging the tube end near the after portion thereof to form a trailing corner flap having diagonal fold lines; mechanism for cyclically varying the angular velocity of the leading corner flap forming fingers for increasing the angular speed thereof during the period of contact with the bag tube; and mechanism for operatively interconnecting said conveyor with said angularly shiftable pairs of

fingers for maintaining a preselected relationship between the speed of advance of the bag conveyor and the angular velocity of said fingers.

8. A bag bottom opening and spreading device comprising in combination: a conveyor for advancing a bag tube along a predetermined path; mechanism for bending an end of said tube to a position approximately at right angles to the body of the tube; mechanism for thereafter partially opening the tube end; a tube end spreading unit comprising a plurality of pairs of fingers which move angularly in synchronous relationship to one another and to said conveyor, one of said pairs being adapted for entering the partially open tube end and spreading same to form side flaps for a bag bottom, a second pair of fingers adapted for entering said open tube end near the leading edge thereof for folding same along diagonal fold lines to form a corner fold flap, and a third pair adapted to engage the tube end near the trailing edge thereof and folding same along diagonal fold lines to form a second corner fold flap, and mechanism for adjusting the phase relationship of said fingers to said conveyor while both are in operation.

EDWIN E. BURROUGHS.
